UNITED STATES PATENT OFFICE

120,732

DESIGN FOR A PHOTOGRAPHIC PRINT DRIER

John J. Grabfield, Cincinnati, Ohio, assignor to
General Devices Corporation, Fort Thomas, Ky.,
a corporation of Ohio

Application January 25, 1940, Serial No. 89,695

Term of patent 3½ years

To all whom it may concern:

Be it known that I, John J. Grabfield, a citizen of the United States, residing at Cincinnati, in the county of Hamilton and State of Ohio, have invented a new, original, and ornamental Design for Photographic Print Drier, of which the following is a specification, reference being had to the accompanying drawings, forming a part thereof.

Figure 1 is a front perspective view of a photographic print drier, showing my new design.

Figure 2 is a rear view.

Figures 3 and 4 are opposite end elevational views of the same.

I claim:

The ornamental design for a photographic print drier, substantially as shown.

JOHN J. GRABFIELD.
